UNITED STATES PATENT OFFICE.

FRANCIS BENJAMIN HEALD, OF NOTTINGHAM, ENGLAND, ASSIGNOR TO W. E. & F. DOBSON, OF NEW YORK, N. Y.

DESIGN FOR A BEDSPREAD OR SIMILAR ARTICLE.

SPECIFICATION forming part of Design No. 21,535, dated May 10, 1892.

Application filed April 11, 1892. Serial No. 428,715. Term of patent 7 years.

To all whom it may concern:

Be it known that I, FRANCIS BENJAMIN HEALD, of Nottingham, England, have invented and produced a new and original Design for a Bedspread, of which the following is a specification, reference being had to the accompanying drawing, forming a part thereof, in which the figure is a face view or fac-simile of a bedspread showing my design.

10 The essential feature of my design is the representation of the landing of Columbus produced centrally upon the fabric and the inclosing border having groups of plant-like figures produced therein.

15 The center piece of the design is a fac-simile of the well-known picture of the landing of Columbus, in which the most prominent figure in the foreground is Columbus standing erect, with a drawn sword in one hand and a 20 flag in the other, while grouped around him are his several followers and attendants, and in

the background appears ships riding at anchor, while disposed about are natives, shrubbery, and other figures. The center piece is enclosed by a border, which is broken at the 25 centers and is produced in full lines at the corners, the border having a scalloped exterior edge, from the points of which depend nucleated flower-like figures. Within the border are produced groups of plant-like figures representing sub-tropical and aquatic plants. The corner groups of plant-like figures are connected by flowering plant-like figures, these forming the center of the border.

I claim—

25 The design for a bedspread or similar fabric, herein shown and described.

FRANCIS BENJAMIN HEALD.
